UNITED STATES PATENT OFFICE.

DANIEL J. CARR, OF LONG BEACH, CALIFORNIA.

SUBMARINE LIFE-BOAT.

1,309,563.

Specification of Letters Patent. Patented July 8, 1919.

Application filed November 18, 1918. Serial No. 282,935.

To all whom it may concern:

Be it known that I, DANIEL J. CARR, a citizen of the United States, residing at Long Beach, in the county of Los Angeles and State of California, have invented new and useful Improvements in Submarine Life-Boats, of which the following is a specification.

This invention relates to an attachment 10 to a submarine, whereby the crew may escape to the surface from the submarine, when the latter is submerged.

It is an object of this invention to provide a life boat for a submarine, which can be entered from the submarine, when the latter is submerged, and which can then be released so that it may rise to the surface.

It is another object of this invention to provide a life boat in combination with a submarine so that the exit from the submarine to the life boat may be closed by the occupants of the life boat, thereby permitting salvage of the submarine.

It is a further object of this invention to provide a life boat structure so arranged as not to interfere with the normal operation of the submarine.

I accomplish these objects by means of the embodiment of my invention illustrated 30 in the accompanying drawing, in which:

Figure 1 is a fragmentary longitudinal section through a submarine with my attachment applied thereto, the forward part of the submarine being shown. Fig. 2 is 35 an enlarged fragmentary section taken on the line 2-2 of Fig. 1, only a fragment of the submarine being shown. Fig. 3 is an enlarged fragmentary view in section of the man-hole, showing the details 40 of connection between the various elements. Fig. 4 is a section taken on the line 4-4 of Fig. 3. Fig. 5 is an enlarged fragmentary view in section of the releasing structure shown in Fig. 2, and Fig. 6 is a 45 section taken on the line 6-6 of Fig. 5.

Referring more particularly to Figs. 1 and 2, a submarine is indicated by A. Built upon the submarine is a super-structure indicated by B. This is in general the superstructure, which supports the walking deck. Mounted in the super-structure so as to be released therefrom is a life boat C. A man-hole way D connects the submarine and life boat, providing means of access 55 from the submarine to the life boat. It is usual to divide the submarine into several

compartments separated by bulkheads. There may be several life boats, each communicating with a separate compartment, although, herein I have only shown one, as it sufficiently illustrates the invention.

The super-structure is built up to form an open iron frame work, and has supporting bars 7 conforming to the shape of the bottom of the life boat, and upon which the latter rests. Adjacent the top of the super-structure and extending downwardly are keeper bars 8, which parallel the sides of the life boat.

Referring more particularly to Figs. 1 and 3, the shell 9 of the submarine is provided with a man-hole opening, in which is secured a cylindrical member 10, which extends above and within the shell of the submarine. The upper end of the man-hole 70 way 10 is flanged outwardly as indicated by 11. Secured to the upper face of the flange is a rubber gasket 12 held in place by steel rings 13 and 14. The bottom of the life boat hull 15 is provided with a man-hole opening, 80 which registers with the cylindrical member 10. Placed around the opening in the life boat are openings for dogs 16. A steel bearing 17 is provided for each dog opening, and disposed therein is a brass bushing 18. The upper end of the dog is threaded and provided with a squared wrench hold below the threaded end. The hook 19 of the dog is disposed so that it may be swung underneath the flange 11 of the man-hole way. A dog wrench 20 is mounted upon a squared end of the dog shank, and holding it in position is a cap 21 mounted upon the threaded end. The cap 21 is adjusted so as to tighten the hook of the dog 90 against the flange and compress the gasket 12, thereby making a water tight fit between the man-hole way and the life boat shell. It is obvious that by turning a dog, its hook may be moved off the flange, thereby 95 releasing the life boat from the man-hole way. This operation may be performed from within the life boat.

At the edge of the man-hole opening of the life boat is a ring angle 22. Secured 105 to the angle are brackets 23, to which bolts 24 are pivotally secured. Mounted upon the upper edge of angle 22 is a man-hole cover 25 having a rubber gasket 26 for making a water tight fit with the angle. Fastened to 110 the cover 25 and overhanging the edge thereof is a member 27 having a slot for the

bolt 24 to swing into. The bolts 24 are provided with nuts 28, so that when swung into position for locking, a nut may be tightened to hold the cover 25 in closed position.

The man-hole way is provided with a lip 29 at its lower end. Mounted over the lip 29 and within the submarine is a man-hole cover 30 having a gasket 31 to make a water tight fit with the man-hole way. Pivoted bolts 32 are mounted upon the way and coöperate with a member 33 for fastening the cover in place from within the submarine. Secured to the cover 30 are bolts 34 having dogs 35 for engaging the lip 29 and permitting the man-hole cover to be fastened in place from within the life boat.

Referring particularly to Figs. 2 and 5, the life boat hull is provided with openings in the sides thereof, which are covered with cast steel boxes 36. Shafts 37 are slidably extended through the cast steel boxes and packed by packing boxes 38. On the box 36 is a cradle 39 forming a socket for the ball of a latch 40. Latch 40 is provided with a slot 41, in which rides a pin 42 secured to the shaft 37. When the shaft 37 is moved to its outer position, the latch 40 will be swung to the position shown in dotted lines and will register with the keeper bar 8. A brass facing 43 is mounted upon the keeper bar to provide a non-corrodible surface of contact between the latch and keeper bar. There are a number of these latches, which are disposed in pairs, members of a pair being in alinement on opposite sides of the boat.

Shaft 37 is rectangular at its outer end, where it passes through the cast steel box, and rounded at the other end, which is provided with a thread 44. Referring particularly to Fig. 2, it will be noticed that there is a latch upon the opposite side of the life boat having a shaft 37' in alinement with shaft 37. The thread 44 is right handed, while the thread 44' upon shaft 37' is left handed. A sleeve 45 is mounted upon the ends of the alined shafts, and has internal threads at its ends coöperating with the threads upon the shafts. Secured to the sleeve 45 is a worm wheel 46. A hanger bearing 47 is secured to the shell of the life boat, and journaled therein is the sleeve 45. A similar set of gearing and latches is disposed at the other end of the boat. Referring more particularly to Fig. 1, a worm shaft 48 is journaled in hanger bearings, and meshes with the worm wheel 46 and the corresponding worm wheel at the other end. Mounted upon the shaft 48 are ratchets 49 for turning the shaft. It is obvious that upon turning the shaft 48, the latches will be projected or retracted in synchronism through the intermediate gearing. By this means occupants of the life boat can retract the latches and release the life boat from the super-structure.

The life boat is entirely closed except for the man-hole opening at the bottom and a similar man-hole opening at the top. The top man-hole opening is closed by a cover 50 held in place by bolts 51. It is through the top man-hole that the occupants of the boat can leave upon reaching the surface.

The life boat is placed in position as shown in Figs. 1 and 2, the man-hole covers 50 and 30 being closed. Cover 25 is open. If for any reason the crew are unable to bring the submarine to the surface, they make ready to escape. The cock 52 in door 30 is tried for water. If there is no water, the door 30 is opened and the life boat entered. The door 30 is then hauled up by the air of ring 53, and the dogs 35 set on the lip flange of the way. The door is then fastened in position by tightening the dog bolts. This leaves the submarine protected against the entrance of water. A line having a float secured thereto is attached to the ring 53. Upon release of the life boat, the float will rise to the surface, thereby indicating the position of the submarine. Next, door 25 is closed and fastened in position by bolts 24. This makes both the life boat and submarine secure from the entrance of water. The next step is to slacken the cap nuts 21, and a blow with a hammer on the wrenches 20 will turn the dogs free from the flange 11. This releases the life boat from attachment to the man-hole way, and it is only necessary to release the life boat from the super-structure to free it entirely from the submarine. To accomplish this, the ratchets 49 are turned, operating the worm gear and retracting the latches from the keeper bars. The latches are so arranged that they move in unison so that all become free at the same instant, allowing the life boat to rise to the surface by its own buoyancy. When the life boat reaches the surface, bolts 51 may be released and the man-hole cover 50 opened, allowing the occupants to make their exit from the life boat at the proper time. The submarine remains in position at the bottom with no opening for the entrance of water other than any which may have been occasioned by accident.

As before stated a life boat may be placed over each compartment of the submarine. This assures some measure of escape for the crew in the event of an accident. Those members of the crew who are in the undamaged compartments have a means of leaving the boat and rising to the surface.

It is obvious that stanchions and other suitable means may be added to the super-structure, in order to protect the crew on the walking deck from the wash of heavy seas. However, as this forms no part of my invention, I have shown no such structure.

What I claim is:

The combination with a submarine of a boat forming a water tight compartment, a man-hole way connecting said boat and said submarine, keeper bars secured to said submarine, latches secured to the sides of said boat and slideable into and out of engagement with said keeper bars, shafts held against rotation and slideably disposed in said shell, a shaft being secured to each latch, said shafts

having threads thereon, sleeves held against longitudinal movement and engaged with the threads on aligned shafts, and means to rotate said sleeves in unison for projection and retraction of said shafts, whereby to operate said latches. 15

In witness that I claim the foregoing I have hereunto subscribed my name this 1st day of November, 1918.

DANIEL J. CARR.
